ADJUSTABLE STRIP CUTTING TOOL

Filed July 5, 1947

UNITED STATES PATENT OFFICE

2,601,183

ADJUSTABLE STRIP CUTTING TOOL

Philip H. Unsinger, Fremont, Ohio, assignor to
 Unsinger A P Corporation, Fremont, Ohio, a
 corporation of Ohio

Application July 5, 1947, Serial No. 759,107

4 Claims. (Cl. 30—293)

1

This invention relates to a strip forming device and more especially to an apparatus or device for shearing strips from a larger area of material.

The invention embraces the provision of means for subdividing a strip of wood or the like into narrow strips and is inclusive of adjustable means for obtaining different widths of strips from the supply of material.

The invention comprehends the provision of a device including an adjustable cutter for a strip severing device, the cutter being arranged for adjustment to produce strips of various widths from a supply of material and in which the operative or cutting edge of the tool is enshrouded so that there is no liability for the user to be injured by the tool.

Another object of the invention resides in the provision of a strip forming or shearing device in which a strip may be severed from a supply of material while the device is held in the hand of the operator or the device may be used while mounted upon a supporting surface.

A further object of the invention resides in the provision of a strip forming device adapted to rapidly shear thin strips from a wider strip of material and whereby the portion of the device taking over the strip is adjustable to accommodate material of various thicknesses.

A further object of the invention resides in a strip forming or shearing device in which the cutting or shearing instrumentality is adjustably supported, the device being provided with indexing or gaging means for determining the size of strip to be formed, the combination including a securing means for retaining the cutting tool or instrumentality in adjusted position so that a plurality of strips of identical widths may be formed.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and the drawing of a form of the invention, which may be preferred, in which:

Figure 1 is a top plan view showing one form of my invention with which is illustrated a comparatively broad strip of material from which narrow strips may be obtained;

Figure 2 is a front elevational view of the strip forming device shown in Figure 1;

2

Figure 3 is a side elevational view of the strip forming device;

Figure 4 is a vertical sectional view taken substantially on the line 4—4 of Figure 1;

5 Figure 5 is a vertical sectional view taken substantially on the line 5—5 of Figure 2;

Figure 6 is a sectional view similar to Figure 4 embodying a modified form of cutting instrumentality;

10 Figure 7 is a detail sectional view taken substantially on the line 7—7 of Figure 6, and

Figure 8 is a plan view of one of the elements forming a part of the strip forming device.

While I have illustrated my invention as embodied in means particularly adapted for subdividing or severing strips from a larger strip of wood, it is to be understood that the principles of my invention may be embodied in arrangements for performing various cutting or severing operations upon strip material as for example routing, recessing, fluting, impressing or forming various cross-sectional configurations in strips of material.

Referring to the drawings in detail and especially to the form of invention shown in Figures 1 through 5 inclusive, there is illustrated a frame 10 which is formed with a horizontal portion 11 and a projecting flange 12. Disposed in substantial parallelism with the plate-like portion 11 is a base or member 14 which is secured to the flange portion 12 by means of screws 15. The heads of the screws 15 are preferably countersunk so that their exterior surfaces do not project beyond the lower surface of the base member 14.

35 The space between the plate portion 11 and the base member 14 accommodates the material or wood W from which strips are to be severed or formed. The portion 11 is formed with spaced

40 upwardly extending projections 17 defining an intermediate uniplanar surface 18. The uniplanar surface 18 and walls 20 form a suitable guiding means or way adapted to accommodate a cutter supporting means or member 21. The member 21 is fitted between the projections 17 for relative slidable movement providing for adjustment as hereinafter explained. The member 21 is formed at one end with an upwardly extending portion 22 which is formed on its for-

45 ward face with a recess 23 adapted to receive and accommodate the body portion 25 of a cutting or shearing tool 26. The projection 22 is provided with a threaded bore which registers with an opening in the shank 25 of the cutting tool 26

50 adapted to accommodate a screw 28 for retaining

55

the cutting tool to the projection 22. The member 21 carrying the cutter 26 is slidably adjustable to position the cutter with respect to the flange 12 in order to vary the widths of strips 40 severed from a supply of material W. The portion 11 is formed with a slot 30 to accommodate adjustment of the cutter 26. The member 21 is provided with an elongated slot 31 through which extends a screw or bolt 32 and which is adapted to receive a thumb nut 33 and washer 34, the thumb nut being utilized to secure the cutter supporting member 21 in adjusted position. The body portion 11 is provided with a threaded opening to receive the threads of the screw 32 so that upon loosening or releasing the thumb nut 33 the screw 32 will remain in fixed relation with respect to the portion 11.

The canted face portion of one of the projections 17 is calibrated with graduations 36, and the member 21 is provided with an index line 38 which is adapted for registration with the graduations 36 to indicate the width of strips 40 that may be severed from the large strip or supply W. Thus the graduations 36 may be spaced to represent distances of $\frac{1}{16}$ of an inch or any other unit of measurement. The inner face 41 of the portion 12 provides the guiding means or initial positioning means for the material W and the distance of the cutter 26 from the guiding face 41 determines the width of the severed strip 40.

Means are provided whereby the device may accommodate materials of various thicknesses. In the form of the invention disclosed, this means is in the form of a resilient member 43, the same being shown per se in Figure 8. Member 43 is formed with a centrally disposed projection 45 provided with an opening 46 to accommodate the passage of the bolt or screw 32. As shown in Figures 1 and 5, the central portion of member 43 is also formed with a recess 47 coextensive with the slot or recess 30 in portion 11 to accommodate the relative movement of the cutting instrumentality 26. The member 43 is provided with resilient portions 49 which are curved toward the base plate 14 as shown in Figure 4. The extremities of portions 49 extend upwardly as at 50 adjacent the ends of portion 11 and plate 14. The curved portions 49 and 50 are joined by curved sections or configurations 51. The portions 49 are integrally joined with the central or uniplanar portion 52, the juncture being configurated by ridge portions 53, as shown in Figure 4. These ridges are for the purpose of adding strength or stiffness to the central portion 52 so that the latter will lie in coextensive relation with the lower surface of portion 11. Each of the curved portions 49 are formed with a series of spaced parallel slots 54 to render the portions 49 resilient so that they may be readily flexed into engagement with the wood or material to be severed by the device.

The upper portion of base plate 14 is formed with a groove or depression 56 to accommodate the apex or point of the cutter 57 which projects into the groove for the purpose of insuring the severing of thin strips of material.

The device of my invention may be utilized when disposed upon a surface such as a table top or the device may be used while held in the hand of the operator. The user first pre-determines the width of strips to be sheared or cut from a source of supply of wood or other material. This is accomplished by releasing the thumb screw 33 and slidably adjusting member 21 until the index line 38 is in registration with proper graduation 36 representing the width of the strip to be ob-

tained. This adjustment positions the cutter or shearing tool 26 a proper distance away from the guide face or surface 41, this distance being equal to the width of the strip which will be obtained from the device. The thumb screw 33 is then drawn up or tightened to secure member 21 in fixed relation to the body portion 11. If the operator chooses to hold the device in his hand, the block or supply of wood W may be forced into the device at either side with one edge of the supply W in engagement with the guiding face 41. The resilient portions 43 of the strip retaining means are flexed in an upward direction as viewed in Figure 4 to accommodate the entrance of the wood supply W. The curved portions 51 on member 43 and the curved portions 55 on the base plate 14 facilitate the entrance of the wood W into the device. The wood supply is maintained in engagement with the guide face 41 as the wood is brought into contact with the cutting edges of cutter 26. It should be noted that the cutting edges 27 are formed by bevel configuration as indicated in Figures 3 and 4, so that the bevel tends to hold the edge of the wood supply in close engagement with the guiding face 41 while the strip 40 is being severed therefrom. Thus after the operator or user has started the cutter 26 through the wood supply, the angle or bevel 27 of the cutter serves to thereafter urge the wood into contact with the guiding face 41 during the entire cutting operation so that a uniform width of strip is fashioned or sheared from the supply W. It should be noted that the flexible member 43 renders the device adaptable to receive blocks of woods of varying widths up to a thickness that will pass through the space between the central ledges 53 formed on member 43 and the upper surface of the base 14.

40 The device may be used by placing the same upon a table top or other suitable surface, holding the device against movement with respect to such surface and forcing the wood supply W through the device.

45 Figures 6 and 7 illustrate the arrangement of my invention embodying a different form of shearing or cutting tool. Mounted upon the projection 22 and disposed within the recess 23 is a member 60 which is secured to the projection 22 by a screw 28. The lower portion of member 60 is provided with a kerf 61 which is of a width suitable to accommodate a circular cutter or wheel 62 having a radial beveled portion 63 forming a cutting edge 64. The cutting wheel 62 is suitably journaled on a stub shaft 66 disposed in aligned openings provided in the furcations formed by the kerf 61. In the use of a circular cutter of the type disclosed the plate 14 is formed with a concavity 68 to provide clearance for the cutting wheel 62. With this type of cutting or shearing tool, the same may rotate on the shaft 66 during strip shearing or cutting operations.

50 While the frame construction and member 21 are illustrated as formed of molded plastic, it is to be understood that the construction may be made of metal or other suitable material.

55 It is apparent that, within the scope of the invention, modifications and different arrangements may be made other than is herein disclosed, the present disclosure is illustrative merely, the invention comprehending all variations thereof.

60 What I claim is:

65 1. In combination; a strip shearing device including a frame plate having a projecting flange;

said flange forming a guide portion; a member having a portion spaced from said frame plate; means cooperating with the flange on said frame plate and said member for connecting said member and frame plate together; an element mounted upon said plate and slidably adjustable transversely thereof; a strip shearing tool removably supported upon said element and disposed in the space between said frame plate and member; a transversely extending groove formed in said frame plate to provide clearance for said shearing tool; means for securing said element in adjusted position; an arcuately shaped flexible plate connected intermediate its ends to said member for biasing the material to be severed into contact with the frame plate; and means including calibrations formed on said element and said member for determining the space between said tool and said guide portion to regulate the width of strip to be formed.

2. A strip shearing device including a frame formed of plastic material and having spaced uniplanar portions; the space between said uniplanar portions being adapted to receive a supply of material from which strips are to be formed; means including a flexible plate secured to said frame and disposed within said space; said flexible plate being arranged to engage said material at spaced points for urging the same into engagement with one of the uniplanar portions of said frame; an element arranged for adjustment in a direction transversely of the uniplanar portions; a shearing plate of V-shaped form carried by said element and having two cutting edges projecting in the space between said uniplanar portions, and means for securing said element in adjusted position with respect to said frame.

3. A strip shearing device including a frame formed with spaced uniplanar portions; the space between said uniplanar portions being adapted to receive a supply of material from which strips are to be formed; a guide portion formed on said frame; means for urging material from which strips are to be severed into engagement with one of the uniplanar portions of said frame; said means including a flexible plate having its central portion secured to said frame, the portions of said plate disposed either side of the securing means being flexibly biased to normally

- extend across the space between the uniplanar portions of said frame and adapted for engagement with the material from which strips are to be formed; an element slidable transversely of said frame; means for locking said element in adjusted position; a shearing tool secured to said element and having a cutting edge projecting into the space existent between the uniplanar portions of said frame and intermediate the ends thereof; the cutting edge of said tool being beveled on the side adjacent the guide portion to urge the severed strips toward the guide portion formed on the frame.
4. A strip shearing device including a substantially rectangular frame construction of U-shaped cross-section; a strip guiding surface formed on the frame; a shearing tool arranged within the U-shaped portion of said frame construction and intermediate the ends thereof; means including an element transversely adjustable relative to the frame and carried by one of the leg portions of said U-shaped frame for supporting said shearing tool; the space between the leg portions of the U-shaped frame and bounded by the strip guiding surface being adapted to receive material from which strips are to be severed; and means including an arcuately shaped resilient plate secured intermediate its ends to the frame and engageable at its end portions with the material for urging the latter into contact with one of the leg portions of the frame during strip severing operations.
